UNITED STATES PATENT OFFICE.

HENRY LAGERQUIST AND JULIUS P. ANDERSON, OF DES MOINES, IOWA.

SANDPAPERING DEVICE.

1,365,924.

Specification of Letters Patent. Patented Jan. 18, 1921.

Application filed March 19, 1919. Serial No. 298,296.

To all whom it may concern:

Be it known that we, HENRY LAGERQUIST and JULIUS P. ANDERSON, citizens of the United States, and residents of Des Moines, 5 in the county of Polk and State of Iowa, have invented a certain new and useful Sandpapering Device, of which the following is a specification.

The object of our invention is to provide 0 a power operated sandpapering device of simple, durable and inexpensive construction.

More particularly it is our object to provide 15 a sandpapering device of comparatively light weight which includes a suitable handle for manipulating the device and a reciprocating member adapted to receive a sheet of sandpaper, which may be readily installed or removed for replacing with 20 other sandpaper.

With these and other objects in view our invention consists in the construction, arrangement and combination of the various parts of the device, whereby the objects contemplated are attained, as herein more fully set forth, pointed out in our claims and illustrated in the accompanying drawings, in which.

Figure 1 shows a side elevation of a sandpapering device embodying our invention.

Fig. 2 shows a longitudinal, vertical, sectional view through the same.

Fig. 3 shows a horizontal, sectional view taken on the line 3—3 of Fig. 1.

Fig. 4 shows a detail, sectional view taken on the line 4—4 of Fig. 2.

Fig. 5 shows a plan view of the upper surface of one end of the sandpaper holding block.

Fig. 6 shows a detail, sectional view taken through one of the plates of the device illustrating the sliding mounting of the reciprocating member to which the sandpaper holding block is secured.

In the accompanying drawings, which illustrate a form in which our power operated sandpapering machine may be embodied, we have used the reference numeral 10 to indicate generally the upper member 45 of our device, which, for convenience we will call the cover.

The cover 10 has at its forward and rear-

ward ends downwardly extending flanges 11 and 12, and at its sides downwardly extending flanges 13 which are shorter than the end flanges.

On the cover 10 is a gear casing member 14 from which projects a handle 15 which has a central bore forming a journal for a shaft 16. The shaft 16 is mounted in ball 60 bearings 17 and 18 in the handle 15 and the gear casing 16. The outer end of the shaft 16 is connected with a flexible shaft 19.

On the inner end of the shaft 16 within the casing 14 is a beveled gear 20. A short 65 shaft 21 is mounted in the cover 10, and has mounted on it within the device a beveled gear 22 which meshes with the gear 20.

Fixed on the lower end of the shaft 21 is an arm 23. Secured to the arm 23 is a 70 downwardly projecting shaft 24 having on its lower end a head 25 provided with a screw-driver slot 26.

On the shaft 24 is a sleeve or bushing 27. The shaft 24 projects through a plate 28 75 which has a laterally elongated slot 29, surrounding which is an upwardly extending rib 30 for forming a better bearing for the shaft 24.

Suitably supported on the flanges 13 above 80 the plate 28 are shafts 31 on which are roller bearings 32 or other suitable anti-friction devices.

Just rearwardly of the roller 32 adjacent to the handle 15 is a downwardly extending 85 flange 33, and just forward of the forward roller 32 is a downwardly extending flange 34. The purpose of these flanges will be hereinafter more fully explained.

Secured to the flanges 13 by means of 90 screws or the like 35 are side-plates 36, which project below the flanges 13 and have at their lower edges inwardly extending spaced pairs of flanges 37. The two flanges on each side-plate 36 form a guideway in 95 which are mounted anti-friction rollers 38. The side edges of the plate 28 are mounted in said guideways, as clearly illustrated in Figs. 2 and 4.

Secured to the under surface of the plate 100 28 is a sandpaper holding block 39.

The sandpaper holding block 39 is secured to the plate 28 by means of screws 40, the heads of which are countersunk in the block.

39. In one end of the block 39 is a transverse slot 41 designed to receive the edge of a piece of sandpaper 42.

5 Mounted in the other end of the block 39 are bolts 44, the ends of which project beyond the block 39. Mounted on the projecting ends of the bolts 44 is a strip 45. The sand paper may be provided with holes to receive the bolts 44.

10 By screwing the nuts 46 on to the bolts 44 one end of the sand paper may be firmly gripped between the strip 45 and the block 34. The block 39 is provided with rabbets 47 at its sides in its upper surface to receive the lower flanges 37 and the lower edges of the side-plates 36, as illustrated in Fig. 4, and to form guides for the reciprocating movement of the sandpaper block.

15 Formed on the outer surface of the flanges 11 and 12 are ribs 49 to protect the device.

20 In the practical operation of our improved power operated sandpapering device it will be understood that the shaft 19 is connected with a suitable source of power, whereby rotation may be imparted to the shaft 19 and the shaft 16.

25 Rotation is imparted from the gear 20 to the gear 22, and thence to the shaft 21 for operating the arm 23 as a crank.

30 As the arm 23 swings around in a circle, centered at the center of the shaft 21, the shaft 24 is swung around in the slot 29 for thereby imparting reciprocating motion to the plate 28 and to the sandpaper holding block.

35 The flanges 33 and 34 help to keep dust from the sandpaper away from the gearing of the device.

40 It will be seen that the device may be readily and easily taken apart for repair or for replacing any parts that may become worn.

45 The shaft 21 has its upper end screw-threaded to receive a nut for readily installing or removing the shaft and the gearing.

50 The shaft 24 is screwed into the arm 23 so that it may be easily removed.

55 Some changes may be made in the construction and arrangement of the parts of our improved sandpapering device without departing from the essential features and purposes of our invention, and it is our intention to cover by our claims any modi-

fied forms of structure or use of mechanical equivalents which may be reasonably included within the scope of said claims:

We claim as our invention:

1. In a device of the class described, a 60 cover member, having downwardly extending front, and back and side flanges, a handle on said cover member, extending away therefrom, a removable guide on each of said side flanges, a plate slidably mounted in said guides, having a laterally elongated slot therein, a shaft mounted in said handle, a gearing device thereon, an upright shaft mounted in said cover, a gearing device thereon in mesh with said first gearing device, an arm on said second shaft, a third shaft mounted in said arm and projected into said slot, and means for mounting an abrading device on said plate.

15 2. In a device of the class described, a 75 cover member, having downwardly extending front, and back and side flanges, a handle on said cover member, channeled guide devices mounted on said side flanges, a plate mounted for longitudinal reciprocation between said flanges, and having its edges received in said guide devices, means for imparting reciprocatory movement to said plate, means for supporting an abrading device on said plate, said means comprising a 80 block detachably mounted on the under surface of said plate, said block having in one end a slot and having at the other end an adjustably supported strip, a sheet of abrading material having one edge received in 85 said slot and having its other end received between said strip and said block.

25 3. In a device of the class described, a 95 cover member, having downwardly extending front, and back and side flanges, a handle on said cover member, channeled guide devices mounted on said side flanges, a plate mounted for longitudinal reciprocation between said flanges, and having its edges received in said guide devices, means for imparting reciprocatory movement to said 100 plate, means for supporting an abrading device on said plate, anti-friction rollers mounted on said cover, and designed to bear on the top of said plate when said device is 105 in use.

Des Moines, Iowa, May 14, 1919.

HENRY LAGERQUIST.
JULIUS P. ANDERSON.
